STROKE GOVERNOR FOR FREE PISTON ENGINES

Frank M. Lewis, Weston, Mass., assignor to General Machinery Corporation, Hamilton, Ohio, a corporation of Delaware

Application September 12, 1945, Serial No. 615,731

24 Claims. (Cl. 123—46)

1

This invention relates to a stroke governor for free piston engines and more particularly to a device whereby variations in the length of the stroke automatically provide for an increase or decrease in pressure in a bounce chamber to rectify the stroke.

In internal combustion engines of the free piston type, it is customary to provide a bounce chamber wherein air is compressed during working strokes of the engine and this pressure is utilized to return the piston during its combustion stroke. Frequently there are employed two pistons in opposite ends of the combustion chamber and moving in opposite directions. Where this is done the motion synchronized by suitable means which move with or proportionately to the pistons.

In accordance with this invention the movement of the pistons is utilized to govern valves for admitting high pressure air into the so-called bounce chamber or to vent air from that chamber in order to adjust the pressure therein so as to obtain a return of the piston to the desired position at the end of the compression stroke.

In the accompanying drawings forming a part of this specification,

Fig. 1 is a fragmentary side elevation of a free piston engine equipped with features embodying the invention, with parts broken away; Fig. 2 is a diagrammatic illustration of the feature embodying the invention; Figs. 3 and 4 are diagrammatic detail views showing modifications of the governing cam structure; Fig. 5 is a fragmentary modification of Fig. 2 to include an anti "hunting" means; Fig. 6 is a fragmentary detail of a part of the anti "hunting" means in Fig. 5, and Fig. 7 is a different form of stroke governor from that shown in Fig. 2.

In the construction shown in Fig. 2 of the drawings, there are indicated a stationary bracket 9 adjacent to racks 10 and 11 which are in mesh with a pinion 12 so as to move at the same speed in reverse directions. Racks similar to these are frequently connected to the pistons of free piston engines so as to synchronize the movement thereof, as indicated in Fig. 1.

Rack 10 is provided with a cam surface comprising a depression 13 and a projection 14. These are so positioned on the rack that at the end of the compression stroke they pass beneath a roller 15 on the lower end of a plunger 16 guided by bracket 9. On the upper end of plunger 16 there is an adjustable screw 17 in position to contact one arm of a bell crank lever 18 pivoted at 19, the other arm of the lever being connected by

2

rod 21 to a piston 22. Roller 15 is pressed against the cam surface by a spring 20.

Above the piston 22 there is a cylinder providing chambers 23 and 24 on the opposite sides of a piston 25 which is provided with piston rods 26 extending outward in opposite directions. In the construction shown in the drawings, the right end of piston rod 26 projects near one arm of a bell crank lever 27, the other arm of which is operatively connected to a valve 28, which controls communication between a high pressure air line 29 and a pipe 30 leading to the bounce chamber. The other rod 26 projects adjacent a bell crank lever 31, which is operatively connected to a valve 32 controlling communication between pipe 30 and a vent pipe 33.

Piston 22 works in a cylinder providing a chamber 35 on the left of the piston and a chamber 36 on its right. Chamber 35 is connected through a check valve 37 and by-pass 38 to a port 39 into chamber 24, and chamber 36 is similarly connected through check valve 40 and by-pass 41 to a port 42 into chamber 23.

Beneath chambers 35 and 36 there is an accumulator chamber 45. Chamber 45 is connected with chamber 35 through port 46 and through check valve 47 in passage 48. Similarly, chamber 45 is connected to chamber 36 through port 49 and through check valve 50 in passage 51.

Piston 22 is provided with a plunger rod 52 extending in the opposite direction from rod 21 and working in a pump cylinder 53. Oil is supplied to cylinder 53 from line 54 through check valve 55, and is pumped out through check valve 56 and line 57 into chamber 45.

A cylinder 58 has a piston 59 therein dividing the cylinder into two chambers 60 and 61. Chamber 60 is in constant communication with chamber 45, while chamber 61 is in constant communication through line 62 with supply pipe 54. A spring 63 in chamber 61 constantly urges piston 59 to the left. There is a port 64 in cylinder 58 uncovered by the movement of piston 59 to the right, and opening into line 65 connected to line 62.

The operation of the apparatus shown in Fig. 2 can be readily understood from the foregoing description, but for convenience will be summarized as follows:

During the normal operation of the engine, rack 10 moves to the left until, at the end of the compression stroke, projection 14 is underneath roller 15. It will be readily understood that, when depression 13 passes beneath roller 15, piston 22 moves to the left. During the first part

of this movement, oil from chamber 35 flows through port 46 into chamber 45 and thence through port 49 into chamber 36. As the left end of piston 22 covers port 46, the right end uncovers the by-pass 41, and further movement of piston 22 forces oil past check valve 31 into chamber 24, driving piston 25 and rod 26 to the right, the oil from chamber 23 passing through by-pass 41 into chamber 36. This causes the rod 26 to approach bell crank lever 27, but the apparatus is so arranged that ordinarily the rod will not operate the lever to open valve 28. When the roller 15 rides up on projection 14, the reverse action takes place, that is, the initial movement forces oil from chamber 36 through port 49 into chamber 45 and thence through check valve 41 into chamber 35, until port 46 is uncovered, after which the oil passes through that port instead of past the check valve, until port 49 is covered and port 38 uncovered, after which oil is pumped past check valve 40 into chamber 23 and escapes from chamber 24 through by-pass 38, returning piston 25 to the left. In normal operation this movement of the piston 22 to the right will pump twice as much oil into chamber 23 as the movement of the piston 22 to the left, caused by roller 15 dropping into depression 13, pumped into chamber 24. As a matter of illustration, substantially half of the pumping movement of piston 22 as it moves to the right is required to restore piston 25 to its center position while the remaining half of the pumping movement is needed to move piston 25 to the position in which rod 26 is adjacent bell crank lever 31. When rack 10 moves back to the right, the roller moves downward and piston 22 moves to the left, first forcing oil from chamber 35 through port 46 into chamber 45 and thence past check valve 50 into chamber 36, until port 49 is uncovered, after which the roller again enters depression 13, and by this movement pumps sufficient oil from chamber 35 into chamber 24, so as to return piston 25 to its initial, center position.

It will be seen that pumping action takes place only at the ends of the strokes of piston 22, the beginning and middle part of each stroke not affecting the position of piston 25. Thus, the pumping stroke at one end may be repeated without any intervening pumping stroke at the other end.

It will be seen, therefore, that in normal operation of the device there are two strokes of the piston 22 to the left caused by roller 15 entering depression 13 on both strokes of the rack, while there is one stroke of the piston 22 to the right far enough to cause pumping action. For normal operation this one pumping action to the right must be sufficient to equal the two pumping strokes to the left.

If it be presumed that the stroke of the piston 22 to the right is sufficient to balance the two strokes to the left when wheel 15 rides up to the point 66 on projection 14, it will be readily seen that so long as the rack reaches and does not go beyond the point where this occurs there will be no operation of either valve 28 or valve 32. If the stroke is short, and point 66 on cam 14 does not reach a position beneath roller 15, then on each stroke of the engine there is more oil pumped into chamber 24 than is pumped into chamber 23. This difference need not be enough on one stroke of the engine to operate valve 28 but, if the condition is repeated, only a slight failure of the point 66 to reach a desired point

under the roller 15 on each stroke will have such cumulative effect that the piston 25 moves to the right until valve 28 is opened, admitting high pressure air to the bounce chamber. This will increase the forces which return the engine pistons during the compression stroke so as to lengthen the stroke and return the operation to normal. Conversely, if cam 14 moves to the left beyond the point where 66 is directly underneath roller 15, there will be an excess of oil pumped into chamber 23 on each stroke of the engine. One occurrence of such an elongated stroke need not be sufficient to open valve 32, but the cumulative effect of continued excessive strokes would quickly move piston 25 to the left far enough to open valve 32 and vent the bounce chamber so as to reduce the pressure therein until the piston was returned only to the normal position at the end of the compression stroke.

On each stroke of piston 22 to the left, the movement of plunger 52 admits oil past check valve 55 into chamber 53, from which it is driven past check valve 56 and through line 57 into chamber 45 by the return of plunger 52 to the right. Thus, a small amount of oil is pumped into the accumulator chamber 45 on each stroke of the engine, and this is more than enough to take care of any normal leakage. As the amount of oil in chamber 45 is increased by the margin that is pumped over that which is lost, piston 59 is forced to the right against spring 63 until port 64 is uncovered and allows the excess to escape and to return through lines 65 and 62 to supply pipe 54. Any air trapped in the oil beneath the supply pipe may be vented through a suitable valve such as indicated at 67. Air may be vented from other portions of the oil system through valves 68.

By the described mechanism, it will be seen that control valves 28 and 32 are not operated during the normal running of the engine, even if there is some variation in the length of successive strokes; but if the average of the strokes is even slightly longer or shorter than that for which the device is set, prompt adjustment will follow automatically.

While one construction embodying the invention has been illustrated and described in some detail, it will be readily understood that many modifications are possible by which the features of the invention, as defined in the appended claims, might be utilized. In Figs. 3 and 4, there are shown two slight modifications of the controlling cam. In these figures the cams are shown on the edge of a rack-bar 10, as in Fig. 2, but it will be understood that they could be carried by any other part moving in fixed relation to the movement of the piston.

In Fig. 3 there is shown a cam rise 70 located similarly to the left depression 13 shown in Fig. 2, and an additional cam rise 71 located similarly to rise 14 shown in Fig. 2. The pump and control features are not shown in connection with Fig. 3, as they are the same as shown in Fig. 2. However, the connections must be adjusted so that piston 22 is in its left position when roller 15 rides on the smooth upper surface of bar 10, is moved to a middle position when the roller rides up on rise 70, and the first pumping action occurs when the roller rides up on rise 71. On the return movement, the riding of roller 15 down rise 71 returns the piston 22 to a middle position, and the second pumping action occurs as the roller rides down rise 70. With this arrangement, there are normally only two equal

pumping strokes on each reciprocation of the engine piston, instead of being three strokes, one of which equals the other two, as in the construction disclosed in Fig. 1.

Fig. 4 is similar to Fig. 3 except that it shows one continuous cam rise 73 instead of the separate rises of Fig. 3. The construction shown in Fig. 4 is simpler, and is satisfactory where but little variation in stroke length is likely to occur. However, if there is danger of the stroke shortening so that roller 15 will not ride up on the cam rise 73, the construction shown in Fig. 3 can be adopted and avoid that danger.

In Fig. 1 is diagrammatically illustrated an internal combustion free piston engine having a central cylinder 75, forming the combustion chamber, and opposite end cylinders 76 in which latter air compressor and bounce pistons 77 and 78, respectively, operate. A working piston 79 projects inwardly from each set of pistons 77, 78 into said combustion chamber. The fuel injector pump is shown at 80, the fuel or oil pump at 81, and the high pressure air supply for the line 29 indicated at 82, and the bounce chamber with which the line 30 connects is shown at 83. A tank for supplying oil to the pump is shown at 84.

In the operation of the governor, piston 25 is caused to move into or out of chambers 23 and 24, depending upon the character of the working strokes. Such movement of piston 25 may, for some applications or conditions, be over sensitive to stroke characteristics, thereby causing the engine to "hunt." In Fig. 5 is illustrated an apparatus which acts to dampen the action of the piston 25, whereby its movement is caused to be less responsive to overstroke and understroke conditions, and the objectionable "hunting" action of the engine is thereby eliminated. In this modification, chambers 23' and 24' and piston 25' correspond to the chambers 23 and 24 and piston 25 in Fig. 3, and the ports 39' and 42' correspond to the ports 39 and 42 of said figure. Provided on the piston rod 26', at each side of the piston 25' adjacent thereto, is a smaller piston 85 that projects through the end wall of the respective chambers 23', 24', and into the respective chambers 86, 87, whereby outward movements of the pistons 85 in said chambers cause a displacement of fluid therein. The chamber 87 opens through a port 88 into a chamber 89 while the chamber 86 opens through a port 90 into a chamber 91. The chambers 89 and 91 are separated by a piston valve 92 normally held in neutral position therein by springs 93 at each end. The piston 92 is provided with a central recess 94 adapted by movements of the valve to open communication between one or the other of metering ports 95 and 96 and an exhaust port 97. The ports 95 and 96 communicate, respectively, with the chambers 24' and 23', while the port 97 communicates with a passage 98 and line 99 leading to an atmospheric pressure relief, such for instance as the oil tank 84 shown in Fig. 1. Relief ports 100 and 101 open, respectively, from the chambers 89 and 91 to the passage 98 and are controlled by needle valves 102. It is preferable in practice to make the metering ports 95 and 96 of slot-form lengthwise of the piston, as shown in Fig. 6, so that a piston movement will uncover an increasing area of one or the other port.

The operation of this damping or "hunting" preventing apparatus is as follows: Assuming piston 25' is caused to move in a left-hand direction,

due to an overstroking condition of the power pistons, as previously explained in connection with Fig. 2, the left-hand piston 85 displaces oil from chamber 87 through port 88 into chamber 89. 5 Due to the close restriction of port 100 by needle valve 102, the volume of chamber 89 is increased temporarily by the addition of oil and thus the piston valve 92 is caused to compress the opposing balancing spring 93 and to shift in a right-hand direction, thereby uncovering the metered orifice 96. Direct communication is thus provided from chamber 23' through the restriction of the orifice 96, lines 97, 98 and 99 to an atmospheric relief. Further pumping of oil by piston 22 (Fig. 15) then will only produce very gradual movement of piston 25' since a relatively large amount of oil will pass through orifice 96. Piston valve 92, due to the balancing action of the springs 93, assumes its neutral location upon the cessation 20 of movement of piston 25'. Such movement of said piston is permitted by the slow escape of oil through the restricted port 100. A return movement of piston 25' is also retarded by the identical action as described above, except only that 25 the device is in operation in the reverse order. Thus, it will be seen that the charging and venting of the direct bounce chamber is dependent on a gradual and controlled movement of piston 25', and that charging and venting are not permitted to follow one another in rapid sequence.

In the modified form of stroke governor shown in Fig. 7, 110 designates a piston synchronizing rack-bar having a cam-raise 111 thereon, 112 is the roller riding on the rack-bar and cam and 35 carried by a truck 113 having an arm 114 projecting therefrom for the purpose hereinafter described. The truck 113 acts through a pivoted arm 115 against the lower end of a reciprocably movable rod 116 to raise said rod against the 40 tension of a spring 117 when the roller travels up the cam 111. After a predetermined lost motion raising of the rod 116, it strikes the lower end of a rod 118 and causes a raising of a piston 119 in a chamber 120 against the tension of a 45 spring 121. The chamber 120 at the spring side of the piston has connection with a chamber 122 through a port 123, and at the other side of said piston is in connection with said chamber 122 through a passage 124 having two ports 125 and 126 opening into the chamber 122. The port 125 is controlled manually by a needle valve 121 and the port 126 is controlled by a check valve 128, which opens inwardly toward the chamber 120. The chamber 122 has connection with an oil 50 pressure supply source through a line 130 corresponding to the line 54 in Fig. 1. A rod 131 projects from the spring pressed side of the piston 119 and is provided without the chamber 120 with two slots or recesses 132 and 133 spaced 55 longitudinally of the rod. At one side of the rod 131 is a casing 134 having a passage 135 in communication through a line 136, corresponding to line 30 in Fig. 1, with the direct bounce chambers 83 of the engine. This passage has an air pressure supply connection 137 normally closed by a needle valve 138, and also has a pressure relief line 139 to the atmosphere that is controlled by a normally closed needle valve 140. The valves 138 and 140 are opened by movements of respective bell crank levers 141 and 142 having arms 60 projecting freely into the respective slots 133 and 132 for lost motion connection with the rod 131 when moved. The truck arm 114 is connected by a bell crank lever 143 and connecting rod 144 to a piston 145 in a chamber 146 having connection 65 70 75

through a line 147 to the scavenging receiver 148 of the engine. This receiver, as well understood in the art, has air compressed therein by the pistons 11 on their outward strokes and such receiver has connection with the combustion chamber of the engine to supply scavenging air thereto during the engine exhaust period. A spring 149 acts on the piston 145 in opposition to the pressure in the chamber 146.

The operation of this modified form of the invention is as follows: When the engine pistons are near but short of the ends of their compression strokes, the cam 111 engages roller 112 and raises rod 116. This movement of rod 116, when its lost motion has been taken up, raises plunger 119, forcing oil from the chamber 120 above the piston into the chamber 122. At the same time oil enters the chamber 120 at the lower side of the piston through the port 126 past non-return valve 128. On the return stroke of the rack 110, the plungers 116 and 118 lose contact. Plunger 118 is urged downward by the spring 121, but can only return slowly as the oil leaks through controlled orifice 125. The plunger 118 is thus given a small reciprocating motion which will tend to center about a fixed position. If the compression strokes of the engine pistons are normal, the movements of rod 131 and its slots 132 and 133 are such that no motion is imparted to levers 141 and 142 due to their lost motion connection with the rod. Should the engine pistons stop short of their proper compression strokes, roller 112 will not rise as high on cam 111 as normal. On the subsequent stroke, rod 118 will move down further toward the rod 116 than normal and bell crank lever 141 will then be operated to open the valve 138 to admit air pressure from line 137 to passage 135 and consequently to the direct bounce chambers of the engine. Should the pistons 79 have an overstroke condition and come too close together, the cam 111 will be pushed to the right beyond normal, thus causing a lifting of the roller 112 and raising of the rod 131 to actuate the lever 142 to open the vent valve 140, permitting air to be released from the passage 135 and the direct bounce spaces to the atmosphere. Upon an increase in pressure in the scavenging receiver 148 above a normal operating pressure, the piston 145 is moved down in its chamber, thus causing a movement to the left of the truck 113, so that it will travel a greater distance up the cam 111 during each compression stroke of the engine pistons. It is thus apparent that the greater the pressure in the scavenging receiver the greater will be the raising movement of the roller 112 and accordingly the piston 119 and its rod 131 so as to release pressure from the bounce chambers through the passage 135 until the engine stroke has been lessened in accordance with the increased pressure in the scavenging receiver. This arrangement, whereby the position of the cam roller is varied in accordance with the pressure in the scavenging receiver, could be similarly applied to roller 15 of Fig. 2 as well as to roller 112.

Other variations of cam construction and operation than those shown may be devised and also modifications of the pumping device, but the above description makes clear the principle of the control device and will enable those skilled in the art to make such further modifications, within the scope of the appended claims, without additional illustration or description.

What I claim is:

1. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, and connections from said member operating the valve means when the end of the stroke of the member caused by the compression stroke of the piston is short of its normal position to open the passage from the bounce chamber to said source of compressed gas and when said stroke goes beyond its normal position to open the passage from the bounce chamber to the vent.

5 2. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, and connections from said member operating the valve means when the end of the stroke of the member caused by the compression stroke of the piston is short of its normal position to open the passage from the bounce chamber to said source of compressed gas and when said stroke goes beyond its normal position to open the passage from the bounce chamber to the vent.

10 3. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, a valve operator having a neutral position from which it is movable in one direction to open one of said valves and in the opposite direction to open the other of said valves, and means actuated by repeated short strokes of the engine piston to open the valve controlling the passage from said source to the bounce chamber, and actuated by repeated long strokes of the engine piston to open the valve from the bounce chamber to the vent.

15 4. Apparatus in accordance with claim 2, and the last said means comprising a pump and a connection from said member actuating said pump at the compression end of the engine stroke.

20 5. Apparatus in accordance with claim 2, and the last said means comprising a pump and a connection from said member actuating said pump at the compression end of the engine stroke.

25 6. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, a cylinder, a piston in the cylinder, connections from the piston operating said valves alternatively when the piston moves in opposite directions, a pump for forcing liquid into said cylinder and moving the piston, and connections from said member operating the pump at the compression end of the engine stroke.

30 7. Apparatus in accordance with claim 4, comprising a cam surface carried by said member and operating said connections near, but short of, the compression end of the engine stroke to actuate the pump in the direction to open the valve in the high pressure line and a cam surface carried by said member for actuating the pump in the direction to open the vent valve when said member moves beyond its normal position at the compression end of the engine stroke.

35 8. In an internal combustion engine of the free piston type having a member moving in fixed relation to the movement of the engine piston, a free piston stroke regulator comprising a pump cylinder and piston and control valves rendering the piston effective for one pumping action when in the latter portion of its movement towards one end of the cylinder and for another pumping action in the latter part of its movement towards the other end of the cylinder, means actuating the pump piston from said member, and means controlled by the pump for lengthen-

ing or shortening the stroke of the engine by proportionately greater pumping at one end of the pump cylinder than at the other.

7. In an internal combustion engine of the free piston type having a member moving in fixed relation to the movement of the engine piston, a free piston stroke regulator comprising a pump cylinder and piston and control valves rendering the piston effective for one pumping action when in the latter portion of its movement towards one end of the cylinder and for another pumping action in the latter part of its movement towards the other end of the cylinder, means actuating the pump piston from said member, and means controlled by said pumping actions for shortening and lengthening the stroke respectively.

8. In an internal combustion engine of the free piston type having a member moving in fixed relation to the movement of the engine piston, a free piston stroke regulator comprising a pump cylinder and piston and control valves rendering the piston effective for one pumping action when in the latter portion of its movement towards one end of the cylinder and for another pumping action in the latter part of its movement towards the other end of the cylinder, a cam surface on said member, a roller in position to be contacted by said surface as the engine piston nears and leaves the end of its compression stroke, and connections from the roller moving the piston in accordance with the movement of the roller.

9. Apparatus in accordance with claim 8 and in which portion of the cam surface first encountered by the roller as the engine piston approaches the end of its compression stroke is shaped to produce stroke-lengthening action of the pump piston and the portion of the cam surface last encountered by the roller at the end of said compression stroke is shaped to effect stroke-shortening action of the pump.

10. In an internal combustion engine of the free piston type having a bounce chamber compression in which chamber drives the engine piston on its compression free piston stroke, means to govern the stroke at its compressing end comprising a source of gas under high pressure, a valve to connect said source to the bounce chamber, a venting valve for the bounce chamber, a member moving in fixed relation to the movement of the engine piston, a pump, connections from said member to the pump operating the pump variably in accordance with variations in the length of the stroke of the engine piston at the compression end of its stroke, a valve-controlling piston arranged to leave both of said valves closed when the said piston is in an intermediate position and to open the high pressure valve by movement in one direction and to open the vent valve by movement in the other direction, and means to control the position of the valve-controlling piston by the action of the pump and move it in the first said direction when the engine stroke is shorter than desired and in the other direction when the engine stroke is longer than desired.

11. In an internal combustion engine of the free piston type having a bounce chamber compression in which chamber drives the engine piston on its compression free piston stroke and a member moving in fixed relation with the engine piston, stroke-controlling means comprising a pump actuated by said member when said member is at the portion of its movement cor-

responding to the compression end of the engine stroke and varying the action of the pump in accordance with the length of the stroke, and means governed by the variation in the pumping action to increase the pressure in the bounce chamber when the said stroke is shorter than desired and to decrease the pressure in the bounce chamber when the stroke is longer than desired.

12. In an internal combustion engine of the free piston type having a bounce chamber pressure in which chamber drives the engine piston on its compression free piston stroke and a member moving in fixed relation with the engine piston, a pump cylinder, a piston in the cylinder, and means providing valves and ports for pumping into one outlet only as the piston moves from the middle of the cylinder towards one end thereof and through another outlet only as the piston moves from the middle of the cylinder towards the other end thereof, means operating the piston for pumping action in one end of the cylinder by movement of said member short of the normal end of the compression stroke of the engine and operating the piston for pumping action in the other end of the cylinder to an equal extent at the end of the normal stroke of the member, to a lesser extent when the stroke is short and to a greater extent when the stroke is long, and means actuated by the pumping of liquid from the first said outlet to increase pressure in the bounce chamber and actuated by liquid from the second said outlet to decrease pressure in the bounce chamber.

13. In an internal combustion engine of the free piston type comprising a bounce chamber and a member moving in fixed relation to the movement of the pistons, a free piston stroke control device comprising a source of compressed gas, means providing passages from said source to the bounce chamber and from the chamber to a vent, valve means controlling said passages, connections from said member operating the valve means when the end of the stroke of the member caused by the compression stroke of the piston is short of its normal position to open the passage from the bounce chamber to said source of compressed gas and when said stroke goes beyond its normal position to open the passage from the bounce chamber to the vent, and means associated with said connections and operable to dampen the action thereof to prevent "hunting" of the engine.

14. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, a valve operator having a neutral position from which it is movable in one direction to open one of said valves and in the opposite direction to open the other of said valves, means actuated by repeated short strokes of the engine piston to open the valve controlling the passage from said source to the bounce chamber, and actuated by repeated long strokes of the engine piston to open the valve from the bounce chamber to the vent, and hydraulic means operating in connection with said valve operator to dampen its action and eliminate engine "hunting."

15. In an internal combustion engine of the free piston type comprising a bounce chamber and

a member moving in fixed relation to the movement of the piston, a free piston stroke control device comprising a source of compressed gas, means providing passages from said source to the bounce chamber and from the chamber to a vent, valve means controlling said passages, a cylinder, a piston in the cylinder, connections from the piston operating said valves alternatively when the piston moves in opposite directions, a pump for forcing liquid into said cylinder and moving the piston, connections from said member operating the pump at the compression end of the engine stroke, and hydraulic means in connection with said cylinder operating to dampen the action of said pumped liquid on the piston in the cylinder to eliminate "hunting" of the engine.

16. In an internal combustion engine of the free piston type comprising a bounce chamber and a member moving in fixed relation to the movement of the piston, a free piston stroke control device comprising a source of compressed gas, means providing passages from said source to the bounce chamber and from the chamber to a vent, valve means controlling said passages, a cylinder, a piston in the cylinder, connections from the piston operating said valves alternatively when the piston moves in opposite directions, a pump for forcing liquid into said cylinder and moving the piston, connections from said member operating the pump at the compression end of the engine stroke, and means in connection with said cylinder operable by movement of the piston in said cylinder to effect a metered release of pumped liquid pressure from the cylinder to dampen the action of the liquid on the piston to prevent "hunting" of the engine.

17. In an internal combustion engine of the free piston type having a member moving in fixed relation to the movement of the engine piston, a free piston stroke regulator comprising a pump cylinder and piston and control valves rendering the piston effective for one pumping action when in the latter portion of its movement towards one end of the cylinder and for another pumping action in the latter part of its movement towards the other end of the cylinder, means actuating the pump piston from said member, means controlled by said pumping actions for shortening and lengthening the stroke respectively, and means automatically operable to dampen said pumping action on said last means to prevent "hunting."

18. In an internal combustion engine of the free piston type having a direct bounce chamber and a member moving in fixed relation to the movement of the engine pistons, a free piston stroke regulator comprising a pump cylinder and a piston therein, said cylinder being open at one side of its piston to a liquid pressure supply source, valve means regulating the communication between said pressure source and the other side of said piston, a spring urging movement of said piston in one direction, means actuating said piston in the other direction from the movement of said member, means in connection with said bounce chamber and having an air pressure supply port and a vent port, and means controlling said ports and operable by movements of said piston to either admit pressure to or vent it from said connection when predetermined running conditions are present in the engine.

19. In an internal combustion engine of the free piston type having a direct bounce chamber, a member moving in fixed relation to the movement of the engine pistons, a free piston stroke

regulator including a connection with said bounce chamber and having a fluid pressure supply port and a vent port, a normally closed control valve for each of said ports, and means actuated by predetermined overstroke movements of said member to open said vent valve and hydraulically actuated when understroke movements of the member occur to open said pressure supply valve.

20. In an internal combustion engine of the free piston type having a direct bounce chamber, a scavenging pressure receiver and a member moving in fixed relation to the movement of the engine pistons, a free piston stroke regulator including a connection with said bounce chamber and having a fluid pressure supply port and a vent port, a normally closed control valve for each of said ports, means actuated by predetermined overstroke movements of said member to open said vent valve and hydraulically actuated when understroke movements of the member occur to open said pressure supply valve, and means in connection with and operable by scavenging receiver pressure to vary the extent of member actuated movement of said first means whereby increased pressure in said receiver over normal will cause an opening of said vent valve and decreased pressure therein under normal will cause an opening of said pressure supply valve.

21. In an internal combustion engine of the free piston type having a direct bounce chamber, a scavenging pressure receiver and a member moving in fixed relation to the movement of the engine pistons, said member having a cam lift theron, a free piston stroke regulator including a normally closed valve operable to admit air pressure to the bounce chamber, a second normally closed valve operable to permit escape of air pressure from said chamber, a truck having movements imparted thereto by said cam transverse to the member movement at or near a limit of stroke movement of the member, means operable by a variance in pressure from normal in said receiver to shift the position of said truck lengthwise of the member to have an early or late engagement with the cam lift in a compression stroke of the engine pistons, and means controlled by cam actuated movement of the truck to open said vent valve upon a predetermined overstroke condition of the engine pistons and controlled at least partially by fluid pressure to open said supply valve upon a predetermined understroke condition of the pistons.

22. In an internal combustion engine of the free piston type comprising a bounce chamber, a bounce chamber, a scavenging pressure receiver and a member moving in fixed relation to the engine piston, free piston stroke control device comprising a source of compressed gas, means providing a passage from said source to the bounce chamber and a passage from the bounce chamber to a vent, valves controlling said passages, connections from said member opening the valve in the first said passage when the compression stroke of the piston is short of a predetermined normal range, and opening the valve in the second said passage when the compression stroke of the piston is longer than a predetermined normal range, and means predetermined said normal range in accordance with the pressure in said receiver.

23. In an internal combustion engine of the free piston type comprising a bounce chamber, a scavenging pressure receiver and a member moving in fixed relation to the piston, free piston stroke controlling means comprising a source

of gas under pressure, a valve controlling connection of said source to the bounce member, a vent valve for the bounce member, a cam on said member, connections operated by the cam to open the first said valve when the compression stroke of the piston is shorter than a predetermined normal range and opening the second said valve when said stroke is longer than said range, and means changing its position with changes of pressure in said receiver and adjusting said connections to make the said normal range shorter as the pressure in said receiver increases and to make said range longer as the pressure in the receiver decreases.

24. In an internal combustion engine of the free piston type comprising a bounce member, a scavenging pressure receiver and a member moving in fixed relation to the piston, free piston stroke control device comprising a source of gas under pressure, means providing a passage from said source to said chamber and a passage from said chamber to a vent, a cam on said member, a roller contacted by said cam near the compression end of the piston stroke, connections from said roller opening the first said pas- 15

sage when the cam travels less than a predetermined distance after contacting the roller and opening the vent when the cam travels more than a predetermined distance after contacting the roller, a cylinder, a control piston in the cylinder, means connecting the cylinder on one side of the piston to pressure in the receiver, a spring exerting pressure against the other side of the piston, and connection from the piston to the roller moving the roller to contact the cam earlier as the pressure in the receiver increases and later as the pressure in the receiver decreases.
